C. MUEHLEISEN.
TYPOGRAPHICAL COMPOSING AND DISTRIBUTING MACHINE.
APPLICATION FILED NOV. 21, 1916.
1,221,361. Patented Apr. 3, 1917.

UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPGRAPHICAL COMPOSING AND DISTRIBUTING MACHINE.

1,221,361.

Specification of Letters Patent.

Patented Apr. 3, 1917.

Application filed November 21, 1916. Serial No. 132,648.

To all whom it may concern:

Be it known that I, CARL MUEHLEISEN, a citizen of the United States of America, residing at Chausseestrasse 23, Berlin, N. 4, 5 in the Empire of Germany, have invented new and useful Improvements in Typographical Composing and Distributing Machines, of which the following is a specification.

10 This invention relates to typographical composing and distributing machines such as those known commercially under the trade mark "Linotype", and particularly to those which are provided with a plurality 15 of superposed adjustable magazines and a corresponding plurality of distributors.

It has heretofore been proposed to construct a machine with a plurality of superposed magazines capable of being moved 20 arcually so as to bring one or other of them into operative register with a common assembler plate entrance, to enable composition to be effected from any of the said magazines. These movements of the magazines 25 however, could not be effected without disturbing the angular relationship of the latter to the stationary distributors. This disturbance is negligible in machines having but few magazines, but in machines 30 provided with a large number of magazines, wherein a change may involve the movement of the magazines through a considerable angle, the disturbance may be so great as to seriously impede the passage of the matrices 35 from a distributor into its respective magazine.

According to the present invention the just-named difficulty is entirely overcome by constructing the machine so that when the 40 magazines are adjusted for making a change, the distributors themselves move with them and maintain their relationship to the said magazines.

In the accompanying drawings:—

45 Figure 1 is a side elevation of sufficient of a machine to illustrate the present invention, this machine, as regards the number of magazines employed, being given merely as a convenient example, and

50 Fig. 2 is a rear elevation of a detached portion of the same, drawn to a larger scale than is Fig. 1.

55 a is the pertinent part of the machine frame, b^1, b^2, b^3, b^4, b^5 , and b^6 , are six superposed magazines, and c^1, c^2, c^3, c^4, c^5 , and

c^6 are six distributors respectively appertaining to the said magazines.

All the magazines b^1 to b^6 , and distributors c^1 to c^6 are mounted in a frame d which, by co-axial studs e , (one at each side thereof) is pivoted in the machine frame a , and above the axis of these pivots is located a primary distributor f which separates the matrices according to font. On leaving the primary distributor f , the matrices drop according to font into one of six channels g , whose mouths are alined beneath said distributor, and which conduct them to the respective distributor c^1 to c^6 which distribute them according to character, each into 60 its respective magazine channel. The magazine entrances h are pivotally attached to the pivoted frame d , in groups of three each, which groups can be rocked respectively about the axis of two co-axial pivots h^1 or h^2 65 (one on each side of the frame d) either collectively as groups, or individually.

To provide for the turning of the frame d together with the magazines b^1 to b^6 , distributors c^1 to c^6 and magazine entrances h as 70 a single entity, about the axis of the pivots e , so as to bring any of said magazines into operative register with the assembler plate entrance t , a toothed rack i is pivoted at n to the frame d , and meshes with a pinion k 75 which can be rotated in either direction by a crank handle m , through bevel gear m^1 , the constant engagement between the rack i and pinion k , being maintained by a roller o bearing on the back of said rack.

For checking the movement of the frame d , in those positions in which a magazine is in correct register with the assembler plate entrance t , the magazine frames r , on which said magazines respectively rest, are 80 each provided with a spring catch or equivalent s adapted to engage with a socket in an arm p fast to the machine frame a . The magazine frames r are all rigidly secured to, and between, upstanding arms d^1 forming 85 part of the frame d , in the upper part of which latter the distributor screws q are journaled as shown best in Fig. 2; the construction is such that the magazines can be 90 readily removed from the point of the machine, when occasion requires.

Having described my invention, I declare that what I claim and desire to secure by Letters Patent is:—

1. In a typographical composing and dis- 110

tributing machine, the combination with a plurality of magazines angularly adjustable in the main frame to bring each of them into operative relationship to a common assembler plate entrance, of a plurality of distributors each adapted to separate matrices according to character and deliver them into one of the magazines, angularly adjustable with the magazines without disturbing the 10 relationship between said distributors and magazines.

2. In a typographical composing and distributing machine, the combination with a plurality of magazines and a corresponding plurality of distributors, each adapted to 15 separate matrices according to character and deliver them into its associated magazine, of a frame supporting the magazines and distributors, and pivots connecting the said frame to the main frame of the machine, so that the magazines, frame and distributors 20 can move angularly about the pivots as one entity.

3. In a typographical composing and distributing machine, the combination with a plurality of magazines, a corresponding plurality of distributors, each adapted to separate matrices according to character and a corresponding plurality of magazine 25 entrance channels each connecting one of the distributors with its respective magazine, of a frame supporting the magazines, distributors and magazine entrances, and pivots connecting the said frame to the main frame of the machine, so that the magazines, frame, 30 distributors and magazine entrances can move angularly about the pivots as one entity.

4. In a typographical composing and distributing machine, the combination with a plurality of magazines angularly adjustable in the main frame to bring each of them into operative relationship to a common assembler plate entrance, of a corresponding plurality of distributors, each adapted to 40 separate matrices according to character, and a corresponding plurality of magazine entrances each connecting one of the distributors with its respective magazine, the said 45 distributors and magazine entrances being angularly adjustable with the magazines without disturbing their relationship mutually or with the said magazines.

5. In a typographical composing and distributing machine, the combination with a plurality of magazines, a corresponding plurality of distributors and a magazine entrance operatively connecting each distributor with its associated magazine, of a frame 55 supporting the magazines and their distributors, pivots connecting the said frame to the main frame of the machine, so that the magazines can move angularly, and pivots connecting the magazine entrances to the 60 movable frame so that the said entrances 65

can move angularly with the frame and magazines and can be turned on their pivots out of operative position.

6. In a typographical composing and distributing machine, the combination with a plurality of magazines, a corresponding plurality of distributors, and a frame supporting the magazines and distributors and pivotally connected to the main frame, of a corresponding plurality of channels mounted 75 in the pivoted frame with their mouths in alinement, and each of which is connected with one of the distributors, and a primary distributor adapted to deliver matrices into the 80 said mouths.

7. In a typographical composing and distributing machine, the combination with the main frame, of a frame pivotally supported therein, corresponding pluralities of magazines, magazine entrances, distributors and 85 matrix channels all mounted in and movable with the pivoted frame, the matrix channels adapted to conduct matrices to the respective distributors and having their mouths in alinement, and a primary distributor adapted to deliver matrices into the 90 said mouths.

8. In a typographical composing and distributing machine, the combination with the main frame, of a frame pivotally supported 95 therein, corresponding pluralities of magazines, distributors and matrix channels fixedly mounted in and movable with the pivoted frame, the matrix channels adapted to conduct matrices to the respective distributors and having their mouths alined, a primary distributor adapted to deliver matrices into the said mouths, and a corresponding plurality of magazine entrances pivoted to the pivoted frame so that they can move 100 angularly with the frame and magazines, and can be turned independently of the 105 magazines and distributors out of operative position.

9. In a typographical composing and distributing machine, the combination with the main frame and a stationary assembler plate entrance therein, of a plurality of magazines angularly adjustable in the main frame 110 to bring each of them into operative relationship to the assembler plate entrance, corresponding pluralities of magazine entrances, distributors and matrix channels all angularly adjustable with the magazines, the matrix channels adapted to conduct 115 matrices to the respective distributors and having their mouths in alinement, and the magazine entrances adapted to conduct matrices from the distributors to the respective magazines, and a primary distributor 120 mounted in the main frame and adapted to deliver matrices into the said mouths in all 125 positions of the magazines.

10. In a typographical machine, the combination of a plurality of magazines to con- 130

- tain matrices of different fonts, a primary distributor to separate the matrices according to font, a plurality of character distributors, one for each magazine, to receive 5 the matrices from the primary distributor after their separation according to font, and a movable supporting frame carrying the magazines and character distributors and adapted to bring any selected magazine into 10 operative position without disturbing the connection between the character of distributors and the primary distributor.
11. In a typographical machine, the combination of a primary distributor to separate 15 the matrices according to font and supported in the fixed machine frame, a plurality of distributors each adapted to separate matrices according to character, tubes or channels leading from the font distributor to 20 the respective character distributors, and a pivoted supporting frame wherein the said character distributors and connecting tubes are mounted, said frame having its pivot located in close proximity to the font distributor so as to maintain the operative connection of the connecting tubes therewith in 25 any of the frame's different positions.
12. In a typographical machine, the combination of a plurality of magazines mov- 30 ably arranged so that any selected one thereof may be brought into operative position, a corresponding plurality of character distributors arranged to be moved with the magazines to maintain their operative connection therewith, and a primary distributor 35

to separate the matrices according to font and deliver them to their respective character distributors in any of the different positions of the latter.

13. In a typographical machine, the combination of a plurality of magazines mov- 40 ably arranged so that any selected one thereof may be brought into operative position, a primary distributor to separate the matrices according to font, and distributing 45 mechanism to receive the matrices from the font distributor and separate them according to character for delivery into their corresponding magazines, the said character distributing mechanism being arranged to be 50 moved with the magazines so as to maintain an operative connection therewith without destroying its operative relation to the primary distributor.

14. In a typographical machine, the combination of a plurality of magazines, and distributing mechanism for delivering matrices thereto, the said mechanism including a longitudinally ribbed or permuted bar for 55 each magazine and a system of conveying 60 screws for propelling the matrices along the bars, with a movable supporting frame carrying both the magazines and the distributing mechanism, for the purpose described.

In witness whereof I have hereunto set 65 my hand in the presence of two witnesses.

CARL MUEHLEISEN.
